The ornamental design of an exercise platform with two arms, as shown and described.

DESCRIPTION

FIG. 1 is a perspective view showing my design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof.

The broken lines depict environment and form no part of the claim. The broken lines immediately adjacent to the shaded surfaces define the bounds of the claimed design and form no part thereof.

1 Claim, 6 Drawing Sheets(56)
